UNITED STATES PATENT OFFICE.

ARCHIE MYERS, OF SACRAMENTO, CALIFORNIA.

PET-COCK-OPERATING DEVICE.

Application filed December 13, 1924. Serial No. 755,650.

To all whom it may concern:

Be it known that I, ARCHIE MYERS, a citizen of the United States, residing at Sacramento, county of Sacramento, State 5 of California, have invented certain new and useful Improvements in Pet-Cock-Operating Devices; and I do declare the following to be a full, clear, and exact description of the same, reference being had to the accompanying drawings, and to the characters of reference marked thereon, which form a part of this application.

The invention relates to attachments for Ford automobiles and particularly to a 13 means for operating the oil-test pet-cocks which are mounted on the crank case, and by means of which the level of the oil in said crank case is gaged by the operator.

The principal object of my invention is to 20 provide a device for the purpose adapted to be permanently mounted on the car which will enable said pet-cocks to be more easily and conveniently operated than is possible with the ordinary equipment.

Another object is to provide a device of 25 this character so arranged that after the cocks have been opened by the operator they will be automatically closed without any attention on his part being necessary. I thus provide a safe-guard against the pet-cocks being left open, which of course 30 would, if unnoticed, soon cause a draining of the oil from the crank case.

A further object is to construct the device in such a manner that it may be easily installed in position without making any changes on the car, and while handy to operate, will be concealed from normal view at all times.

A further object of the invention is to 45 provide a device so constructed that with a single handle member both pet cocks may be opened, but the upper one will always be opened first a sufficient distance to cause the oil, if any, to drip from said cock before the lower one is opened, the opening of the lower cock being optional and not being done if a test of the upper cock shows plenty of oil in the crank case.

A further object of the invention is to 50 produce a simple and inexpensive device and yet one which will be exceedingly effective for the purposes for which it is designed.

These objects I accomplish by means of 55 such structure and relative arrangement of

parts as will fully appear by a perusal of the following specification and claims.

In the drawings similar characters of reference indicate corresponding parts in the several views:

Fig. 1 is a perspective view of the device showing the same as connected to standard parts of a Ford car.

Figs. 2 and 3 are front views of the device looking sideways of the car to which the 65 device is attached showing the operating handle in its closed and opened positions, respectively.

Fig. 4 is a fragmentary detail view of the 70 pet-cock handle rods showing the form of connection between the two.

Fig. 5 is a perspective view of a pet-cock handle clamp.

Referring now more particularly to the 75 characters of reference on the drawings, the numeral 1 denotes the crank case of a Ford engine having in the usual location upper and lower pet-cocks 2 and 3. These cocks are turned for my purpose, if not already in such position, so that their handles 4 project toward the adjacent side of the car. These handles in the type of pet cock used on Ford cars are flat members which, when closed and with the cocks turned to the above stated position, are disposed in vertical planes. A quarter turn from this position opens the cocks to their fullest extent.

My operating device includes a rod 5 disposed transversely of the car and projecting from under the mud-guard or fender 6 of the car toward the upper cock 2. On the inner end of the rod is fixed a U-shaped clamp member 7 between the sides of which the handle 4 of the cock is adapted to project, a screw 8 passing through the clamp beyond said handle to pinch the sides of the clamp into frictional engagement with the handle. The inner end of one of the clamp sides has inwardly projecting and spaced ears 9 between which the stem of the handle 4 passes so that the latter may be definitely aligned with respect to the clamp.

The outer end of the rod 5 is bent in a plane at right angles to said rod to form a suitable operating handle 10, the outer end of which is adapted to abut against the under side of the fender 6 when the cock is closed.

The handle 10 has a suitable curvature in 110 a vertical plane between its outer and its

connection with the rod proper so that a loop is provided clear of the fender to enable the handle to be easily grasped, as shown in Fig. 2.

5 The rod 5 adjacent the handle 10 is supported by and journaled in a sleeve 11 formed at one end of a rigid strip 12 which is curved to substantially conform to the contour of the fender 6. This strip extends 10 rearwardly to a termination under the running board 13 of the car. The inner bolt 14 which secures the members 6 and 13 together is also used to secure the strip 12 thereto. The latter has a hole through 15 which the bolt passes, the nut 15 of said bolt being first removed to allow the bolt to pass through the strip.

Just inwardly of the sleeve 11 the rod 5 has a downwardly projecting arm 16 to 20 which one end a tension spring 17 is connected. The other end of the spring has an eye adapted to pass over the bolt 14 after the strip 12 is in position. The nut 15 is then replaced and tightened up, thus 25 binding the parts 6, 13, 11 and the eye of the spring 17 firmly together.

It will thus be seen that if the handle 10 is pulled around toward the front end of the car the cock 2 will be opened and the 30 tension on the spring 17 will be increased. As soon as the operator lets go of the handle the spring will act to turn the rod in the opposite direction, thus closing the cock. Although the spring is still in tension 35 the rod will not be turned beyond said cock closing position on account of the fact that the outer end of the handle 10 will then abut against the fender 6 as shown in Fig. 2, thus of course preventing further 40 movement of the rod 5.

I have also provided a connection between the rod 5 and the lower cock 3 so that the latter will be opened in common with the upper cock 2.

45 This connection comprises a rod 18 similar to but shorter than the rod 5, and having on its inner end a clamp 19 similar to the clamp 7 and adapted for connection to the handle 4 of the lower pet-cock. On 50 said other rod adjacent its outer end is rigidly fixed a plate 20 through which the

rod 5 slidably passes. The rod 5 outwardly of the plate 20 has fixed thereon a rigid plate 21 through which the rod 18 slidably passes, as shown in Fig. 4, the plates 20 55 and 21 being substantially parallel to each other. This forms a substantially rigid connection between the two rods so that one must turn with other. At the same time the slidability of the two rods relative to 60 each other permits of independent connection of the rods to their respective pet-cock handles and takes care of any slight discrepancy which may exist in the length of the rods relative to the position of the pet- 65 cocks.

From the foregoing description it will be readily seen that I have produced such a device as substantially fulfills the objects 70 of the invention as set forth herein.

While this specification sets forth in detail the present and preferred construction of the device, still in practice such deviations from such detail may be resorted to as do not form a departure from the spirit of the 75 invention, as defined by the appended claims.

Having thus described my invention what I claim as new and useful and desire to 80 secure by Letters Patent is:

1. An operating device for petcocks disposed in vertically spaced relation including a pair of rods, means on said rods for attachment to the handles of the pet-cocks, a handle on one of said rods, and connecting 85 means between the rods arranged to cause both rods to turn together after the handle has been turned through a certain arc and enabling the connection with the pet-cock handles to be individually made without 90 disconnecting the rods from each other.

2. An operating device for pet-cocks disposed in vertically spaced relation including a pair of rods, means on said rods for attachment to the handles of the pet-cocks, 95 a handle on one of said rods, and spaced plates extending between the rods, one plate being fixed on one rod and freely slidable on the other, and the other plate being oppositely connected.

In testimony whereof I affix my signature.
ARCHIE MYERS.
